UNITED STATES PATENT OFFICE.

JERVIS R. HARBECK, OF DETROIT, MICHIGAN, ASSIGNOR TO KEMIWELD CAN COMPANY, OF DETROIT, MICHIGAN, A CORPORATION OF MICHIGAN.

TUBE-MANDREL.

No. 869,902.

Specification of Letters Patent.

Patented Nov. 5, 1907.

Application filed May 27, 1907. Serial No. 375,791.

To all whom it may concern:

Be it known that I, JERVIS R. HARBECK, a citizen of the United States, and a resident of Detroit, in the county of Wayne and State of Michigan, have invented 5 a new and useful Tube-Mandrel, of which the following is a specification.

My invention relates to mandrels upon which sheets or bands of paper or other fibrous material may be wound for forming tubes, and consists in mandrels 10 which are longitudinally grooved so as to form corrugated surfaces.

In the accompanying drawings, Figure 1 is a view of a corrugated mandrel and stripping sleeve. Fig. 2 is a transverse cross section of the mandrel. Fig. 3 is a 15 transverse cross section of the mandrel and sleeve. Figs. 4 and 5 are transverse sections of other forms of mandrels.

Similar reference characters refer to like parts throughout the several views.

20 Winding mandrels are generally so constructed that the forward edge of the sheet of tube material or the front end of the band of such material is held against the mandrel either by suction, through the action of an air pump, or a gripper. The revolving mandrel then 25 turns and winds the tube material upon itself. As this material is generally coated with liquid glue and has therefore expanded, it usually contracts to a certain extent immediately upon being wound, thus causing the finished tube to grip the mandrel. I have found that 30 this grip is so strong that the tubes are often injured when they are pushed off the mandrel.

To reduce the frictional area I form longitudinal grooves 1 in the mandrel 2. I have also found that where a cylindrical sleeve slides over a cylindrical mandrel, the edge of one or more wraps of the tube material 35 is liable to become wedged in between the sleeve and mandrel. To prevent this, I form the sleeve 4 with teeth 5 which fit the grooves 1. With such construction, it is impossible for the material 3 to get between the mandrel and sleeve excepting where the mandrel 40 is not grooved, such as the portion 6 having the suction holes 7, but this space is so short that the trouble is immaterial.

In Fig. 5 I have shown a generally rectangular mandrel 8 having grooves 9, and a sleeve 10 having teeth 11 45 to fit the grooves.

In Fig. 4, the edge of the tube material instead of being held by air pressure, is gripped by the clamp 13 mounted on the pin 14. The mandrel 15 has grooves 16 and the sleeve 17 has teeth 18. 50

Having now explained my improvements, what I claim as my invention and desire to secure by Letters Patent is:

A mandrel for winding tubes having a series of longitudinal grooves, and a sleeve slidably mounted on the 55 mandrel and formed with teeth to enter the grooves.

In testimony whereof I have signed this specification in the presence of two subscribing witnesses.

JERVIS R. HARBECK.
